UNITED STATES PATENT OFFICE.

ALBERT P. BALL, OF DETROIT, MICHIGAN, ASSIGNOR TO SQUARE D COMPANY, OF DETROIT, MICHIGAN, A CORPORATION OF MICHIGAN.

SWITCHING DEVICE.

Application filed November 23, 1921. Serial No. 517,165.

My invention relates to switching devices, and it has particular relation to devices of the character designated, wherein means are provided which ensure that the movable switch contacts will be completely engaged with the stationary contacts upon a closing movement of a switch operating handle or analogous device.

5 Numerous difficulties are encountered in

10 the use of switches because of the incomplete closure of the movable contacts. The failure to close the movable contacts far enough so that the full area of contact between the movable blades and the stationary parts is

15 utilized for current conducting purposes results, of course, in unsatisfactory and inefficient operation of the switch. The opportunity for leaving the switch in a half closed condition is especially present with

20 enclosed switches since the operator is unable, with such switches, to see the contacts and determine by inspection whether they are completely engaged.

My invention is particularly advantageous 25 for use with enclosed switches and to this end means are provided, whereby, unless the switch operating handle is so manipulated that the contacts are completely closed, the handle will be automatically returned to full

30 open position of the switch, and the operator will be apprised of the fact that he has not exerted a sufficient force to completely close the contacts. In a switch embodying my invention, the movable contacts are con-

35 stantly biased to open position, such biasing effect being overcome, when the movable contacts are completely closed, by a latch which is effective only upon such complete closure. If, therefore, the operator does not

40 give a sufficiently positive actuation to the switch operator to cause the latch to engage the movable contacts, the handle will, upon being released, automatically snap back into an open position.

45 A further object of my invention is to provide a novel form of link mechanism whereby the above positive closure may be ensured and one of such character that the same is very quickly and simply assembled.

50 To this end I provide a link of but three parts and one wherein the operator may be associated with the link with a minimum of effort and time. I also provide means whereby a spring may be utilized in said link

without its being in any way attached 55 mechanically thereto. Such a provision results in a lowering in the cost of making the device since it is, of course, unnecessary to seat the spring in position by securing the same to either of the moving parts.

60 For a better understanding of my invention, reference may be had to the accompanying drawings, in which—

Figure 1 is a plan view of an enclosed switch embodying my invention, the cover 65 thereof being broken away to show the interior construction;

Fig. 2 is an elevational sectional view taken on the line 2—2 of Fig. 1;

Fig. 3 is a sectional view taken on the line 70 3—3 of Fig. 2, and

Fig. 4 is a sectional view taken on the line 4—4 of Fig. 3.

Referring now more particularly to the drawing, a switch casing 10 is provided with 75 a cover 11 and has mounted therein a switch base 12. Upon the latter are mounted a plurality of fixed contacts 13—13 as well as a plurality of fuse clips 14—14. Movable contacts 15—15 are pivotally mounted on 80 posts 16—16 which are, in turn, mounted on the base 12. These movable contacts are biased constantly to open position by a spring 17, one arm 18 of which embraces the movable contact 15, whereas the other arm 85 19 embraces the post 16.

A switch operator 20 is integrally formed and is mounted to journal in the sides of the casing 10, the portion thereof outside of the enclosing casing being formed as a handle 90 20. The movable contacts are rigidly connected to a cross-head 21 which is attached thereto through the medium of clamps 22.

Pivotally mounted on the cross-head 21 is a link comprising a main unitary member 23 which has a hook 24 formed at its lower end. At its other end this member 23 is recessed, as at 25, and in this recess the bail portion of the operator 19 is received. The recess is closed by a pair of plates 26 and 27 which are secured to said member 23 by cotter pins 28 and 29, the latter passing through the body of the member 23.

The plates 26 and 27 are recessed oppositely to the recess formed in the member 23, this recess being best shown in Fig. 4, where-in it is designated as 30. The plates are also bulged or bowed at 31 whereby, when they

are placed on opposite sides of the member 23 and their recessed portions downwardly directed, a barrel which embraces a spring 31^a, is formed. It will further be observed that 5 the above method of forming a composite link seats the switch operator member 20 in an elongated slot, one end of which is formed by the end of the recess in the member 23 and the other end of which is formed by the 10 ends of the recesses 30 in the plates 26 and 27. The spring 31^a is rigidly held in desired position without there being any necessity of securing the same to any of the link portions. Those skilled in the art will recognize 15 the marked advantages which result, especially with regard to simplicity of assembly, from utilizing my invention to form a composite link which shall have a spring so positioned therein that the movable contacts are 20 snapped open after they have been initially and positively actuated.

The hook 24 encounters, as the switch contacts are moved to closed position, a roller 32 which is mounted on a yoke 33 of a spring 34, 25 the latter being mounted in a pocket 35 formed in the base 12. The association of the link with the cross-head 21 as well as the position of the spring 34 and roller 32 are such that the hook 24 is entirely obstructed 30 in this switch closing movement by the roller 32. However, when the handle 20^a is positively urged in a switch closing direction, the hook 24 rides over the roller 32 and at the same time presses it slightly to the left 35 (Fig. 2). Immediately after the hook portion is moved downwardly sufficiently far, the roller 32 is snapped thereover by the spring 33, and positive closure of the movable contacts is thereby ensured. The spring 33 40 at the same time opposes the biasing effect of the spring 17, which latter otherwise would snap the movable contacts to open position. It is, therefore, evident that a complete closure of the switch contacts is necessary with 45 a switch embodying my invention. Otherwise, when the handle 20^a is released and the resistance of the spring 33 has not been overcome whereby the hook is latched by the latter, the spring 17 functions to snap the movable contacts into open position.

On the other hand, when the handle 20^a is given a switch opening movement, the operator 19 travels to the upper end of the slot 30 and in so doing compresses the spring 31^a. 55 When the operator presses positively against the upper end of the slot 30, it tends to rotate the link slightly to the left, whereupon the hook 24 is disengaged from the roller 32. Upon the release of the movable contacts, the 60 spring 17 exerts a force to throw the contacts to open position. This force is, however, greatly augmented by the power which has been stored up while the spring 31^a was being compressed by the movement of the operator 65 20 in the slot 30.

From the above description of my invention, it will be apparent that I have associated with a switch a very desirable safety device which insures such positive closure of the movable contacts as obviates those difficulties which have heretofore been experienced from incompletely closed contacts. 70

Moreover, I have accomplished this by the use of a link, between the switch operating member and the movable contacts, which is 75 formed of few parts and which is so simply assembled that a marked reduction in cost is obtained through the practicing of my invention.

While I have described but one embodiment of my invention, I believe that the above described device, especially the link utilized therein, and the method of assembling the same, are entirely novel. I, therefore, desire that my invention be broadly interpreted and that the same be only limited by the scope of the appended claims and by the showing of the prior art. 80

What I claim as new and desire to secure by Letters Patent is:

1. In a switch, stationary contacts, movable contacts, an operator, and a link pivotally mounted with respect to said movable contacts and having a lost motion connection with said operator, said link comprising a member having a recess to receive said operator and another member having a slot co-operating with said recess and closing the end of said recess and forming a stop for the operator. 90

2. In a switch, stationary contacts, movable contacts, an operator, a link pivotally mounted with respect to said movable contacts and having a lost motion connection with said operator, and a spring for snapping said movable contacts open, said link comprising a member having a recess to receive said operator and members for closing the end of said recess and for embracing said spring. 95

3. In a switch, stationary contacts, movable contacts, an operator, a link pivotally mounted with respect to said movable contacts and having a lost motion connection with said operator, and a spring for snapping the movable contacts open, said link comprising a member having a hooked lower end to ensure the complete closure of said movable contacts and plates mounted on opposite sides of said member to complete said link. 100

4. In a switch, stationary contacts, movable contacts, an operator, a link pivotally mounted with respect to said movable contacts and having a lost motion connection with said operator, and a spring for snapping the movable contacts open, said link being recessed at its upper end and having a hooked lower end, the recess receiving the operator, and said link further comprising plates 105

which are mounted on the upper end thereof to close the end of said recess to form a slot in which said operator works.

5. In a switch, stationary contacts, movable contacts, an operator, a link pivotally mounted with respect to said movable contacts and having a lost motion connection with said operator, and a spring for snapping the movable contacts open, said link being recessed at its upper end and having a hooked lower end, the recess receiving the operator, and said link further comprising a pair of plates on opposite sides of the upper end of said main link member, said plates together 10 forming a barrel which permanently positions said spring between said operator and a stop formed by said plates.

6. In a switch, stationary contacts, movable contacts, an operator, a link pivotally mounted with respect to said movable contacts and having a lost motion connection with said operator, and a spring for snapping the movable contacts open, said link being recessed at its upper end and having a hooked lower end, the recess receiving the operator and said link further comprising a pair of plates on opposite sides of the upper end of said main link member, said plates being bulged outwardly and oppositely to form 25 a barrel which permanently positions said spring between said operator and a stop 30

formed by said plates, and said bulged portions being recessed oppositely to the recess in the main link member, whereby the association of said plates and said member eventuates a slotted link having a spring so positioned therein that the contacts are snapped open. 35

7. In a switch, stationary contacts, movable contacts, an operator, a link pivotally mounted with respect to said movable contacts and having a lost motion connection with said operator, means for insuring the complete closure of said movable contacts, comprising a spring adapted to be engaged 40 by said link only when the movable contacts are pressed home with an appreciable force. 45

8. In a switch, stationary contacts, movable contacts, an operator, a link pivotally mounted with respect to said movable contacts and having a lost motion connection with said operator, means for insuring the complete closure of said movable contacts comprising a spring carrying a roller adapted to be engaged by said link only when the 50 movable contacts are pressed home with an appreciable force, said link being provided with a hook which pushes said roller aside and thereafter engages the same. 55

In witness whereof, I have hereunto subscribed my name.

ALBERT P. BALL.
